DESIGN FOR A CIRCULAR RIDING DEVICE

Clifford I. Sweet, Delphos, Ohio

Application December 18, 1935, Serial No. 60,152

Term of patent 7 years

To all whom it may concern:

Be it known that I, Clifford I. Sweet, a citizen of the United States, residing at Delphos, Allen County, Ohio, have invented a new, original, and ornamental Design for a Circular Riding Device, of which the following is a specification, reference being had to the accompanying drawing, forming part thereof.

The single figure of the drawing is a perspective view of a circular riding device embodying my new design.

I claim:

The ornamental design for a circular riding device, as shown.
